Des. 367

Dupee Arnold of Providence R. I.
Letters Patent No. 367 Dated April 15, 1851.

The Schedule referred to in these Letters Patent, and making part of the same.

To all Persons to whom these Presents shall come:

Be it known

that I, Dupee Arnold, of Providence, in the County of Providence & State of Rhode Island, have produced a new and original design for the front, side, and back plates of a Cooking Stove; and I do hereby declare that the said new design is fully described and represented in the following specification and accompanying drawings, to which reference is hereinafter made.

In plate 1, fig. 1, is an elevation of the upper front plate; and fig. 2 is a horizontal section of the same, taken in the plane of the line A.B. Fig. 3 is an elevation of the lower front plate; and fig. 4 is a section of the same, taken in the plane of the line C.D. In pl. 2, fig. 5 is an elevation of the side plate. In pl. 3, fig. 6 is an elevation of the back plate, and fig. 7 is a section, taken in the plane of the line E.F.

The outer edges of the top front plate, are ornamented with the mouldings a, b, c. Around each of the four doors are the several mouldings d, e, f, and the cavetto moulding g. The centre of the doors is occupied by the clustered rays h, h, forming a small ellipse, with a raised bead i, in the centre. From this ellipse proceed the raised rays k, k, &c. forming a large ellipse on the panel of the doors; each of these rays being hollowed out, as shown in the drawings. On each side of the upper doors, are the ornamental shields l, l, and on each side of the lower doors are the curved beak-heads m, m, cast in alto relief. Around the lower front plate are the mouldings a, b, c. There are two panels q, q, in this plate, ornamented in the same manner as the doors in the upper plate, and having similar

beak heads on the side. Around the side plates are mouldings, similar to those around the front plates. Around the oven door and the two smaller doors, are mouldings like those at d, e, f & g. in the doors of the front plates, and also the raised moulding r. In the centre of each door are small ellipses, like those in the front plates, formed by the rays h, h, &c. and head i. From the outer edge of these ellipses, proceed the rays s, s - t, t, &c. forming, on the oven and upper door, an elliptical figure; and on the lower door a circular figure, the rays s, s &c. terminating in three leaved flowers u, u, &c. On the side of the oven door are two curved beak heads m, m, and also a similar one on the side of the lower door.

Around the back plate are mouldings like those at a, b, c, around the other plates. In the middle of this plate is the panel x, x, ornamented with an elliptical figure, formed by the rays and flowers y, y, z, z, & a', a' with the small ellipse formed by the rays h, h, &c. On each side of this panel are the small panels b, b, ornamented with elliptical figures like those in the front plates, and with the circular figures c, c, formed by the raised rays h, h, &c.

Having thus described my new design, I shall state my claim as follows:

What I claim as my invention or production, and desire to have secured me by Letters Patent, is the design composed of the several ornamental mouldings and configurations herein above described ^{and represented} in the drawings, for the front, side and back plates of a cooking stove.
